HACK KRAFFT, OF MULBERRY, PENNSYLVANIA.

Letters Patent No. 77,496, dated May 5, 1868.

IMPROVEMENT IN HORSE HAY-FORKS.

The Schedule referred to in these Letters Patent and making part of the same.

TO ALL WHOM IT MAY CONCERN:

Be it known that I, HACK KRAFFT, of Mulberry, in the county of York, and State of Pennsylvania, have invented a new and improved Hay-Fork; and I do hereby declare that the following is a full, clear, and exact description thereof, reference being had to the accompanying drawings, making part of this specification, in which—

Figure 1 is a side view of the front side of the hay-fork, with the several parts thereof adjusted ready for plunging into a body of hay.

Figure 2 is a view of the back side of the fork, showing the parts adjusted in proper positions for grasping and elevating a load of hay.

Similar letters of reference indicate corresponding parts in both figures.

This invention relates to an improvement on forks which are particularly designed for use in the operation of handling and elevating loads of baled hay, wherein ropes and pulleys are employed for facilitating the raising of the loads.

The nature of my invention consists in a rigid rectangular frame, which is suitably braced, and provided with forked ends having jointed points, and also with a central eye-attachment for a suspension-rope, in combination with jointed connecting-rods for moving said pointed ends, which rods are pivoted to and operated by a single vibrating hand-lever having a latching-device applied to it, all as will be hereinafter described.

To enable others skilled in the art to understand my invention, I will describe its construction and operation.

The frame which affords support to the forks while embracing a load to be elevated, consists of two parallel arms, A A, united to a cross-head, A', at right angles thereto. This frame may be readily made of a single piece of metal, by bending it as represented in the drawings. For the purpose of bracing the arms A A and strengthening the frame, a cross-bar, B, is applied to it, which is suitably bent, so that one side of it will be in a plane with the front side of the frame. Another bar, B', having an eye, a, formed on its upper extremity, is suitably applied to the cross-head A' and cross-bar B, in the middle of the width of the frame, for the purpose of affording an attachment for an oscillating hand-lever, C, and also a means for attaching a rope, by which the implement can be elevated with its load of hay or other substance. The bar B' is affixed to the bars A' B, in the middle of the length thereof, for the purpose of suspending the implement centrally.

To the extremities of the parallel arms A A, points b b are pivoted, so as to vibrate inward in the plane of these arms. To these pointed ends b b, rods c c are pivoted, which rods are pivoted at their upper ends to short vibrating-levers d d, and attached to their respective arms by the heads of pins e e, which pins pass through oblong slots e' e' made through the arms, as shown in fig. 1. The lower ends of these rods c c are suitably notched, so as to form, in conjunction with shoulders upon the pointed pieces b b, abutments, which will prevent the points from turning outward in the act of plunging them into a body of hay.

The short levers d d are pivoted to the front sides of the arms A A, and connected, by rods m m, to a cross-head, C', at equal distances from the pivot f of the hand-lever C, as shown in fig. 1. From the rear side of the arm C, near the cross-head A', a stud, g; projects, which is designed to serve, in conjunction with a pivoted latch-piece, D, as a means for locking the lever C in place when the pivoted points b b of the forks are turned inward or at right angles to their arms, as shown in fig. 2. This latching-piece D is constructed with a notch or recess in its lower edge for receiving the pin or stud g, and also with an eye, h, on one end, for allowing the pull-cord to be attached to it, which is used for releasing lever C, and discharging a load when elevated to the proper place for its discharge.

By moving lever C laterally to the position shown in fig. 1, the points b b will be thrown down in lines with their respective arms A A, in which position of the parts the fork is ready to be plunged into a body of hay, the cross-head A' serving as a hand-piece by which to grasp the implement. While the forked arms are in the hay, the lever C is brought to the position shown in fig. 2, and automatically latched by means of the notched piece D. This will bring the points b b to a position at right angles to the forked arms A', and at the same time compress the load within the space enclosed between said arms A' and cross-bar B, and grasp it so firmly as to allow it to be elevated to any desired height.

I am aware that it is not new to employ, in conjunction with a rigid forked frame, turning-points and jointed arms, arranged so as to cause the points to operate as penetrators for the arms of the frame, and then serve as a means for grasping and holding the load, as shown in the patent numbered 64,100, and therefore I do not lay claim broadly to turning-points applied to the arms of a fork-frame.

By my invention, I connect the rods which operate the points to a single hand-lever, and employ a latch which will hold said arm while elevating a load of hay, and then allow the arm to be released, so that the weight of the load upon the points *b* will straighten them out, and thus allow it to fall.

Having described my invention, what I claim as new, and desire to secure by Letters Patent, is—

1. The centrally-arranged vibrating cross-head *C'*, transverse connecting-rods *m m*, rocking-links *d d*, vertically-sliding pivoted legs *c c*, and the forks *b b*, in combination with the frame *A A'*, the whole arranged and operated in the manner shown and described.
2. The latch-lever *D* and pin *g* applied to the frame *A A'*, in combination with a lever, *C C'*, connected to vibrating-points *b b*, substantially as described.

HACK KRAFFT.
